MILK PUMP

Leslie A. Mapes, Palisade, N. J.

Application October 23, 1948, Serial No. 56,203

3 Claims. (Cl. 103—122)

1

The present invention relates to a novel and improved sanitary pump particularly adapted for the pumping of milk, cream and other liquids. Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a vertical central sectional view of a typical and illustrative embodiment of the present invention, taken on the line 1—1 of Figure 2; Figure 2 is a central sectional view taken on the line 2—2 of Figure 1; and

Figure 3 is a cross section taken on the line 3—3 of Figure 1.

The present invention has for its object the provision of a novel and improved sanitary pump which can be easily and rapidly taken apart for cleaning and sterilizing. A further object is the provision of an improved pump which produces a steady flow of liquid with substantially no pulsation of the liquid and with very little turbulence such as might cause churning of milk or cream into butter. A further object is the provision of an improved sanitary pump which minimizes the danger of contamination of the pumped liquid and which is subject to little wear in long periods of operation.

The present invention provides a conveniently accessible pump structure in which the liquid is moved by a pair of rotors, rotating on parallel axes within a single pump chamber which comprises two overlapping generally cylindrical cavities at one side of which is an inlet, while the outlet is at the other side of the pair of cavities. The rotors are each of a somewhat eccentric shape, and are mounted to fill the axial space in the cavities between the bottom of the cavities and the cover member by which the cavities are closed. The rotor shafts are driven by means of a centrally disposed worm meshing with worm gears on the shafts so that the rotors are driven in opposite directions at equal speeds and what wear there is on the gears is equal, the worm

drive at the same time effecting whatever speed reduction is needed from the driving motor.

In order to render assembly and disassembly more convenient and to reduce the possibility of contamination of the liquid by lubricant, the pump chamber is vertically disposed and has its upper end closed by a removable cover. The rotors are preferably splined to their shafts and are supported on the shafts so that the bottom of each rotor rests in substantial contact with the bottom of the pump chamber, while the top of the rotors are in substantial contact with the cover plate. By removal of the cover plate, the rotors are exposed for easy removal by axial movement off the shaft ends, and they are preferably located at a convenient height to be lifted by the operator while standing. While in operation, the rotors are held in place by gravity with only a slight running clearance with the cover plate.

20 Each rotor is formed as a somewhat eccentric member, preferably being truly cylindrical throughout two opposite quadrants, but on different radii, the two cylindrical portions being joined by spiral portions so there is a smooth transition from one cylindrical surface to the other. The rotors are duplicates of each other and are timed so that the large diameter cylindrical portion of one rotor is close to the small diameter cylindrical portion of the other rotor and after 180° of rotation of both rotors, the situation is reversed for the two rotors.

Positioned between the two rotors and closing the space between them is a resilient member bearing against both rotors for their full axial length which member is movable to accommodate the movement of both rotors, thereby separating the inlet and outlet chambers and preventing leakage of the pump at the overlapping portion of the rotor paths.

40 The pump chamber is mounted on the driving housing for easy removal over the upper ends of the driving shafts and is sealed thereto by means of packing rings which can be removed with the pump chamber and replaced separately.

45 It will be understood that the foregoing general description and the following detailed description as well are exemplary and explanatory of the invention but are not restrictive thereof.

Referring now in detail to the illustrative and 50 preferred embodiment of the invention as shown in the accompanying drawings, the driving means for the pump comprises a housing 10 having a cover plate 12 secured thereto by cap screws 14 to form an oil-tight housing in which a worm 16 55 is rotatably journaled by anti-friction bearings

18 and rendered oil-tight by suitable packing members 19 and 20, shaft 16 being adapted to be driven at the desired speed by suitable motor means not shown. Also mounted within the housing and extending vertically through the cover plate 12 are two parallel drive shafts 22, 23 each carrying a worm gear 24 to mesh with the worm 16 and be driven thereby. Each of the vertical shafts 22 and 23 is rotatably journaled by means of anti-friction bearings 26 and 27, the bearings 26 being mounted in suitable seats in the bottom portions of the housing 10 while the bearings 27 are mounted in suitable seats formed in the cover plate 12, the bearings being held on the shaft by means of locking rings 28. As shaft 16 and worm 16 rotate, the shafts 22 and 23 are rotated at a slower speed in opposite angular directions and at equal speeds. Shafts 22 and 23 project upwardly from the cover plate 12 and are adapted to extend into a pump chamber to be supported on cover plate 12.

Pump casing 30 comprises a bottom wall portion 31, side wall portion 32, and a cover portion 34, and the bottom wall portion 31 is grooved to receive a locating spacer bar 36 which also extends into a groove 37 formed on the upper surface of the cover 12, serving to locate and space the bottom wall 31 in the desired spatial relation to the cover plate 12. Suitable packing 38 is provided between the cover plate 12 and the bottom plate 31 surrounding each of the shafts 22 and 23, thereby assisting the shoulders 39 on shafts 22 and 23 in preventing oil creeping up and into the pump casing 30.

Pump casing 30 has its bottom wall 31 formed with two apertures to receive the shafts 22 and 23 and in which these shafts may freely rotate, the space between the bottom wall 31 and the shafts 22 and 23 being sealed by means of the O rings 42 of the usual rubber or other resilient material, being seated in suitable annular grooves surrounding the shafts.

The upper surface of the bottom wall 31 of the pump chamber is preferably flat except for the O ring grooves. Plate 31 together with the side wall member 32 is shaped to provide two slightly overlapping cylindrical cavities 46 of substantial axial length which cavities merge into each other and are connected at one side to an inlet 48 and at the other side to an outlet 50, the inlet and outlet being parallel cylindrical holes which have substantially the same axial extent as the cavities 46 and communicate with the cavities 46 throughout their length. Preferably, and as shown, the centers of the inlet 48 and the outlet 50 are equidistant from the centers of the cylindrical cavities 46.

The upper open end of the pump casing 30 is closed by means of the cover plate 34, which is secured to the wall portion 32 by means of wing nuts on screw studs 54, is provided with an inlet pipe 56 and an outlet pipe 58 aligned respectively with the inlet 48 and outlet 50.

Within each of the cylindrical cavities 46 is rotatably mounted a rotor 60, the two rotors co-acting to draw liquid into the pump through the inlet 48 and expel it under pressure through the outlet 50. Each rotor 60 comprises an eccentric member of an axial length substantially equal to the distance between the upper face of bottom plate 31 and the lower face of cover plate 34, only running clearance being provided. The bottom surface of each rotor 60 normally rests on and contacts with the flat upper surface of the bottom wall 31.

Each of the rotors 60 is of uniform cross section throughout its length, and the two rotors are preferably duplicates of each other. Each rotor is formed with its surface which may be conveniently described as four separate parts. The surface of the rotor from point A to point B is preferably truly cylindrical and of a radius equal to the radius of the cavity 46, neglecting running clearance. The surface of the rotor 60 from point C to point D is also preferably truly cylindrical but of a considerably smaller radius than the portion A B. The surfaces of the rotor from B to C and from A to D are both spirals so that a smooth transition occurs from the surface A B to the surface C D at both sides of the rotor. In other words there is a constant increase per degree in the radius of the curve from C to D and a similar constant increase from D to A. The surfaces A B, B C, C D, and D A are each 90° and the surfaces A B and C D are opposite quadrants.

As will be seen from an inspection of Figure 3, the junctions of the inlet passage 48 with the cylindrical cavities 46 are spaced 90° from the junctions 66 of the outlet 50 with the cylindrical cavities 46 and as the rotors 60 are rotated the space in each cavity 46 is shut off from the inlet 48 at the moment that the space is opened to the outlet 50 and remains closed with respect to the inlet 48 until the rotor has completed 270° of rotation. By reason of the spiral form of the connecting surfaces B C and D A, the right-hand rotor 60 delivers no liquid to the outlet 50 until point B has passed the junction point 66 after which it delivers liquid at an increase in rate until point C passes point 66 at which time the rate becomes constant until point D passes point 66. As point D passes point 66 the rate diminishes and the flow ceases when point A arrives at point 66. During this full rotation of the right-hand rotor 60 the left-hand rotor operates at an equal speed but its action is timed 180° later than that of the right-hand rotor 60 so that it begins to deliver liquid to the outlet 50 just as the right-hand rotor begins to deliver a diminishing quantity of liquid and the left-hand rotor 60 begins to deliver a diminishing quantity of liquid just as the right-hand rotor begins to deliver an increasing quantity of liquid. Thereby substantially all pulsation in the delivery of the liquid is eliminated and a constant rate of flow obtained.

In order to seal the inlet 48 from the outlet 50 between the rotors 60, there is provided a movable member positioned between the two rotors. This member preferably comprises a block 70 of soft, yielding material such as rubber, which is compressed between the rotors 60, having its opposite and relatively long sides cylindrically concave and of a curvature corresponding approximately to the curvature of rotors 60 in the quadrants C D. To form a better wearing surface for the resilient and movable block 70, it is externally sheathed by a relatively thin, flexible metal sheet 72 which, like the rotors and pump chamber, may be conveniently formed of stainless steel and completely surrounds the block 70 except for a narrow gap 74 where the ends of the sheath 72 meet. Block 70 is mounted for sliding pivotal movement between the rotors 60 at their point of adjacency, and extends to fill the space between the bottom wall 31 and the cover plate 34, being held in position by means of a pin or abutment 76 which is held in the shallow slots 75 formed in the cover plate 34 and bottom wall 31.

31, preventing the possibility of block 70 being forced from between the rotors 60. This block 70 thus effectively separates the chambers 46 into inlet and outlet chambers. A second pair of slots 71 may be provided on the opposite side of the rotors 60 and with the pin 76 in these slots the pump may operate in the reverse direction.

Rotors 60 are drivingly connected to their respective shafts 22 and 23 by the upper splined portion of the shafts and the rotors are shouldered to rest on shoulder 78 and lightly in contact with the bottom wall 31 of the chamber.

In pumping liquid such as milk, cream and the like, it is essential that the pump be thoroughly washed, cleaned and sterilized at least daily. Whenever the operation is necessary, it is easily, quickly and effectively accomplished with the pump of the present invention by removal of the wing nuts on screws 54 which allows the cover plate 34 to be removed. After this the rotors 60 may be lifted from their driving shafts 22 and 23 and thereafter the pump chamber 30 as a whole may be lifted off the upper shaft ends so as to permit sterilization of the complete apparatus so far as it ever comes in contact with the liquid being pumped. Due to the fact that the rotors 60 may be lifted upwardly, and may be replaced by reverse movement, and also due to the fact that the normal height of the rotors is at a convenient level, they may be easily handled by the operators, and the operation of this assembly and re-assembly is much simpler and rapid than has heretofore been the case.

By positioning the pump chamber entirely above the driving mechanism and above any parts requiring lubrication, contamination of the milk or other liquid is rendered almost impossible, and any leakage developing in the O rings 42, or between the shafts 22 or 23 and the bottom wall 31, will allow escape of milk from the pump rather than the escape of lubricant into the pump.

Wear on the gears 24 is equalized as they are always subjected to the same movement and forces, and thus there is no danger of their getting out of time and thus developing leakage.

The invention in its broader aspects is not limited to the specific mechanisms shown and described but departures may be made therefrom within the scope of the accompanying claims without departing from the principles of the invention and without sacrificing its chief advantages.

What is claimed is:

1. A sanitary pump including in combination a pump body having a vertically disposed chamber therein, a drive shaft extending vertically in said chamber, said chamber having a substantially flat bottom wall and said chamber being vertically movable onto and away from said shaft, sealing means axially movable along the shaft to seal the upper face of the chamber bottom wall to the shaft, a pump rotor splined to the shaft and held by gravity thereon and against the upper face of the chamber bottom wall, a sealing cover overlying and closing said chamber and contacting with the upper face of the rotor, and inlet and outlet means carried by said cover and

removable therewith whereby the cover, rotor and chamber may be easily disassembled for cleaning and sterilization.

2. A sanitary pump comprising a pump body having a single vertically disposed pump chamber therein, said chamber comprising two cylindrical cavities of equal diameter in slight overlapping relation and having a substantially flat bottom wall and inlet and outlet ports on opposite sides of the chamber, said cavities communicating with the inlet and outlet ports and being positioned adjacent the intersections of the cylindrical cavities, and two rotors which are eccentric with respect to their respective axes of rotation, one rotatable in either cavity, said eccentric rotors running in substantial contact with the cavity walls, each rotor being formed as a generally cylindrical body, two diametrically opposed quadrant surfaces of each rotor being cylindrical and of different radii, said cylindrical quadrant surfaces being connected by spiral surfaces, drive shafts extending vertically in each of said chambers over which the chamber may be lifted, sealing means axially movable along the shaft to seal the upper face of the chamber bottom wall to the shaft, each shaft being splined to receive its rotor and allow the rotor to rest by gravity on the bottom wall, a sealing cover overlying and closing the chamber and contacting with the upper face of the rotor.
3. A sanitary pump as claimed in claim 2 in which a resilient floating member positioned between the two rotors seals the space between them.
